FLOOR TREATING MACHINE

Frederick K. Storm, Jr., Glendale, Calif., assignor to Orbitor, Ltd., a limited partnership of Utah

Filed Oct. 23, 1965, Ser. No. 87,835

Term of patent 14 years

(Cl. D9—2)

FIG. 1 is a side elevational view of a floor treating machine embodying my new design.

FIG. 2 is a top view thereof.

FIG. 3 is a front view thereof.

FIG. 4 is a rear view thereof.

The dominant features of my design reside in the portions shown in full lines, the fragmentary showing of the handle being for illustrative purposes only.

I claim:

The ornamental design for a floor treating machine, as shown and described.
